UNITED STATES PATENT OFFICE.

EDWARD C. RUTTENBERG, OF CHICAGO, ILLINOIS.

DESIGN FOR A PEDESTAL FOR LIGHTING FIXTURES.

Application filed March 7, 1922. Serial No. 1,066. Term of patent 3½ years.

To all whom it may concern:

Be it known that I, EDWARD C. RUTTENBERG, a citizen of the United States, residing at Chicago, in the county of Cook and State of Illinois, have invented a new, original, and ornamental Design for a Pedestal for Lighting Fixtures, of which the following is a specification, reference being had to

the accompanying drawings, forming part thereof.

The figure is a perspective view of the improved lamp or other pedestal.

I claim:

The ornamental design for a pedestal for lighting fixture as shown.

EDW. C. RUTTENBERG.
